UNITED STATES PATENT OFFICE.

ADOLF FRANKE, OF GRUNEWALD, AND ERWIN EHRHARDT, OF PANKOW, NEAR BERLIN, GERMANY, ASSIGNEES TO SIEMENS & HALSKE A. G., OF BERLIN, GERMANY, A CORPORATION OF GERMANY.

TELEGRAPHIC TYPE-PRINTING RECEIVER.

1,126,745.

Specification of Letters Patent.

Patented Feb. 2, 1915.

Original application filed August 19, 1911, Serial No. 644,901. Divided and this application filed February 26, 1914. Serial No. 320,031.

To all whom it may concern:

Be it known that we, ADOLF FRANKE and ERWIN EHRHARDT, subjects of the German Emperor, and residing, respectively, at 5 Grunewald and Pankow, near Berlin, Germany, have invented certain new and useful Improvements in Telegraphic Type-Printing Receivers, of which the following is a full and clear specification.

10 Our invention refers to a telegraphic type-printing receiver, in which the arriving messages are recorded as perforated symbols on a paper strip and in which these symbols are translated into conventional type by 15 means of a translating device. This latter device comprises, in machines known heretofore, a separate machine which is mounted at a distance from the receiving apparatus, as a consequence of such separation between the two apparatuses a considerable 20 time elapses between the receipt of a message and its translation, since preferably the translator is operated only after a certain amount of messages have accumulated. 25 Such separate arrangement has the disadvantage that mutilations of portions of the text or even mutilations of entire messages are discovered very late and their correction is therefore consequently very difficult. 30 Also the attending of these two devices even if they should be mounted close together, would require great attention by the operator or operators. According to the present invention these disadvantages are overcome 35 by uniting the receiver and the translator in one machine so that the translation of the hole symbols takes place immediately subsequent to the perforation of the symbols, and thus the arriving message can be read immediately in printed type. For this purpose a common driving mechanism has been provided by which the feeding of the symbol strip, as also the operation of the other elements of the apparatus, are effected by 40 contact devices; these contact devices control as well the perforating mechanism in the portion of the machine which serves as receiver, as also the printing mechanism of the translating device, whereby the printing mechanism is dependent upon a further contact device which is in turn controlled by the holes in the symbol strip.

In the accompanying drawings our in-

vention is illustrated in substantially diagrammatical form.

The contact device is in substance similar to the one illustrated in our co-pending application, Serial Number 644,901, filed August 19, 1911, from which the present application has been divided.

The receiving apparatus substantially consists of two or more polarizing relays R_1 , R_2 , of the punching apparatus St , which punches the band symbols into the perforated band L , and of the paper feed mechanism VL .

It is assumed in the particular example represented in the drawings that each symbol is formed of only two impulses, differing from each other only in the kind of currents, i_1 , i_2 , positive or negative current impulses, so that four different symbols can be translated in each instance according to whether two positive or two negative impulses, or one positive and one negative impulse is sent. Therefore the receiving ring s_1 of the receiver possesses only two segments r_1 , r_2 , on which the brush b_1 , connected with line L , slides. Polarized relays R_1 , R_2 , which are connected to the two segments r_1 , r_2 respectively, are influenced in such manner by the arriving line currents that for instance only positive currents throw the armatures A_1 , A_2 onto the working contacts h_1 , h_2 respectively; whereas negative currents have no effect on said armatures. The punching magnets M_1 , M_2 of punching mechanism St , which with the punches m_1 , m_2 , operated by their respective armatures, punch the perforated symbols in the band L , are connected to the working contacts h_1 , h_2 .

Shaft W rotates in synchronism with the transmitting device not shown here. Means for operating the shaft synchronism with arriving electrical impulses are known in the art. They are for instance disclosed in the U. S. Patent No. 690,218 of December 31, 1901, to William Duane, and also in the British Patent No. 21,305 of 1903 to Siemens Bros. Illustration and description of such means has therefore been omitted in the present description, so as not to unnecessarily complicate the disclosure of the principal subject matter of the present invention.

As shaft W thus rotates synchronously with the arriving electric impulses a certain punch

can be selected and consequently a certain symbol may be perforated in known manner. The particular magnet of the punching apparatus St energized for the time being attracts its armature and drives the punch M connected therewith as shown, through the band L which unwinds from the drum TL and is moved upward each time after the punching operation by the feed mechanism VL . This feed mechanism comprises two rolls c_1, c_2 , of which c_1 is fast on shaft W . This shaft is operated by means of a ratchet wheel d_1 and a pawl d_2 , the latter being pivotally mounted on one end of a two-armed lever f . The other end of this lever is yieldingly held against a cam g by means of spring f' . The cam is driven by shaft W and at a given moment brings about the operation of the ratchet wheel d_1 and thus of shaft w .

The part of the type-printing receiver forming the translating apparatus comprises the contact device F for reading the perforated band, and a second circuit closing device St_2 , the latter having disks s_2, s_3 , and brushes b_2, b_3 coöperating therewith, and also the printing apparatus D which transforms the symbols perforated in the band L into conventional letters, which are printed onto tape P which is intermittently moved by the feed mechanism VP previously described. The tape P which unwinds from a drum TP is guided between two feed rolls h_1, h_2 , of which h_1 is mounted on shaft w , so that the printed tape is moved at the same rate as the perforated band L . A type wheel T is either mounted directly on shaft W or otherwise suitably driven by it, which type wheel is provided with types t on its periphery, and this wheel rotates closely above tape P . A hammer i forming a portion of the armature of the printing magnet D is arranged on the tape and type wheel. Above the perforated band L are arranged a number of contact springs j_1, j_2 corresponding with the number of rows of perforations. These springs rest with contact feelers z on the perforated band, and when perforations y_2 pass under them they will fall therein and thereby electrically connect contact springs j_1, j_2 with contacts q_2, q_4 respectively. So long as the feelers z slide on the perforated band L they are connected with the contacts q_1, q_3 respectively. The contacts q_1-q_4 are connected with the two slip rings s_2, s_3 and with the segments $y_1, w_1, x_1, z_1, v_1, t_1$ of the second closing device St_2 , whereas the movable contact springs j_1, j_2 are connected to the ends of the coils of the printing magnet D by way of a current source D_1 .

We claim:

1. In a printing telegraph receiver, a main line, a receiver having fixed and movable elements for receiving and distributing cur-

rent impulses arriving over said line, a registering band, a punching device adapted to produce perforations in said band, a selector comprising fixed and movable elements, and a printing mechanism controlled by the perforations punched into said registering band, in combination with means adapted to move synchronously with the current impulses and to drive the registering band and the movable elements of said commutator and of said selector.

2. In a printing telegraph receiver, a main line, a receiver, having fixed and movable elements for receiving and distributing current impulses arriving over said line, a registering band, a punching device, adapted to produce perforations in said band, a selector comprising fixed and movable elements, a type wheel, a printing magnet, and a printing tape coöperating with each other, and a circuit closing device controlled by the perforations punched into said registering band, in combination with means adapted to move synchronously with said current impulses for driving said registering band, said type wheel and said tape, and also the movable elements of said receiving means and of said selector.

3. In a printing telegraph receiver, a main line, a receiver, having fixed and movable elements, for receiving and distributing current impulses arriving over said line, a registering band, a punching device adapted to produce perforations in said band, a selector comprising fixed and movable elements, a type wheel, a printing magnet and a printing tape coöperating with each other, and a circuit closing device controlled by the perforations punched into said registering band, in combination with a shaft rotating synchronously with said current impulses for driving said registering band, said type wheel, and said tape, and also the movable elements of said receiving means and of said selector.

4. In a printing telegraph receiver, a main line, a receiver, having fixed and movable elements for receiving and distributing current impulses arriving over said line, a registering band, a punching device adapted to produce perforations in said band, a selector comprising fixed and movable elements, a printing mechanism and suitable means for controlling it by the perforations punched into said registering band, in combination with an adjusting device for said punching device, and means moving synchronously with said current impulses for driving the registering band and the movable elements of said receiving means and of said selector.

5. In a printing telegraph receiver, a main line, a receiver, having fixed and movable elements for receiving and distributing current impulses arriving over said line, a registering band, punches for producing per-

forations in said band and electromagnets with their appertaining circuits for operating said punches, a selector comprising fixed and movable elements, a printing mechanism and suitable means for controlling it by the perforations punched into said registering band, in combination with relays connected with said receiver and having armatures with suitable circuit connections for controlling the working of said punching magnets, and means adapted to move synchronously with said current impulses for driving the registering band and the movable elements of said receiving means and of said selector.

6. In a printing telegraph receiver, a main line, a receiver having fixed and movable elements for receiving and distributing current impulses arriving over said line, a registering band, and a punching device adapted

to produce perforations in said band, a selector comprising fixed and movable elements, a type wheel, a printing magnet, and a tape, coöperating with each other, and a circuit closing device controlled by the perforations punched into said registering band, in combination with a shaft adapted to rotate synchronously with said current impulses for driving directly said type wheel and the movable elements of said receiving means and said selector, and a second shaft geared to the first one for driving the registering band and the tape coöperating with said type wheel.
